(57) **CLAIM**

The ornamental design for a scalpel, as shown and described.

DESCRIPTION

FIG. 1 is a top view of a scalpel;
FIG. 2 is a bottom view of a scalpel;
FIG. 3 is a first side view of a scalpel;
FIG. 4 is a second side view of a scalpel;
FIG. 5 is a rear view of a scalpel;
FIG. 6 is a front view of a scalpel; and,
FIG. 7 is an upper perspective view thereof.

The broken lines shown in the drawings are included for the purpose of illustrating environmental structures and form no part of the claimed design.
